(57) **CLAIM**

The ornamental design for a head covering, as shown and described.

DESCRIPTION

FIG. 1 is rear view showing my new design in use on wearer's head with drawstrings tied in back of veil.

FIG. 2 is top view thereof, with the veil flared.

FIG. 3 is a side view thereof, with the other side being a mirror image.

FIG. 4 is a front view thereof.

FIG. 5 is a side elevational view thereof, shown in an open configuration.

FIG. 6 is a rear elevational view thereof, showing the inside of the veil; and,

FIG. 7 is a front elevational view thereof.

The broken line showing of a head is for illustrative purposes only and forms no part of the claimed design.
